DRAFT REGULATOR

John W. Miller, Lansing, Mich., assignor to Motor Wheel Corporation, Lansing, Mich., a corporation of Michigan

Application January 3, 1938, Serial No. 182,993

3 Claims. (Cl. 236—45)

This invention relates to draft regulators for combustion apparatus, and more particularly to draft regulators of the type which are adjustable to vary the draft in the combustion apparatus.

5 This invention is an improvement on the regulator disclosed in the application of Don F. Jones, Serial No. 132,675, filed March 24, 1937.

10 Although this invention is adapted for use in any type of combustion apparatus, it is particularly suitable to oil burners of the so-called vaporizing pot type. Oil burners of the vaporizing pot type are particularly sensitive to changes in draft, and consequently it is desirable to provide a draft regulator that will hold the draft 15 in the burner substantially constant within a reasonably wide range of stack drafts.

15 It is accordingly an object of this invention to provide a draft regulator that will be adjustable to vary the draft in the burner but will keep such draft substantially constant when once set at the desired position.

20 Another object of the invention is to provide formulae by means of which the important dimensions of any size of regulator can be readily calculated.

25 In the drawing:

Figure 1 is an elevational view of the improved draft regulator;

Figure 2 is a sectional view taken on substantially the line 2—2 of Figure 1;

Figure 3 is a copy of a curve sheet showing the results of a series of tests under actual working conditions of the regulator disclosed herein in comparison with a regulator of a previous type; and

Figure 4 is a diagram of a regulator blade showing the location of the pivot axis.

Referring now more particularly to the drawing, the numeral 10 designates a pipe which is adapted to be connected to a flue outlet or a stack of an oil burner of any conventional type, not shown. Telescopically inserted in the outer end of the pipe 10 is an annular ring 11 of angular cross-section which is adapted to receive the blade 12 of the regulator.

45 The blade 12 is preferably stamped from a single sheet of metal, and is provided with angular ribs 13 and 14 which tend to stiffen the blade as well as improve its appearance. The blade 12 is slit at a plurality of points 16 and the metal on opposite sides of the slits is pressed in opposite directions in order to provide a support for a pivot shaft 17. The metal of the ring 11 is also slit and deformed at 18 to receive the ends of the pivot shaft 17. In this manner

a freely operating pivot is provided for the blade 12. The pivot axis is located somewhat above the center of the blade 12 so that it divides the blade into a lower or major segment 19 and an upper or minor segment 20.

5 The location of the pivot axis is very important as the proper operation of the regulator is dependent upon the power factor thereof. The power factor of the regulator is determined by the following formula:

$$P. F. = \frac{A' - A''}{A}$$

10 where P. F. is the power factor, A' is the area of the lower segment of the blade, A'' is the area of the upper segment, and A is the total area of the blade.

15 It has been determined experimentally that for best results the power factor of the regulator should be approximately 30%. Stated differently, the ratio of the area of the lower segment to the area of the upper segment should be about 1.375. To produce such a power factor the pivot axis should lie on a chord of the circle subtending 15° of arc. In Figure 4 the chord is designated by the letter C and the angle subtended thereby is designated by the letter E. The center line of the circle is indicated by the letters CL. F designates an angle which is one-half of the difference between the angle E and 180°, or in this case 14°.

20 The perpendicular distance of the chord C from the center line CL of the blade may be determined by the following formula:

$$R - H = R \sin F$$

25 where R—H is the distance desired, R is the radius of the blade and F is the angle shown in Figure 4. Assuming that it is desired to calculate the distance R—H for a blade of 8 1/4" diameter, which would be the proper size for a 9" pipe:

$$R - H = 4 \frac{1}{4} \sin 14^\circ \\ = 4 \frac{1}{4} \times .2419 \\ = .998$$

30 or for all practical purposes, 1 inch.

Near the upper portion of the blade 12 an offset 15 is pressed therein. The center of the circular offset 15 has an opening therein in which is rigidly secured a sleeve 21. The inner surface of the sleeve 21 is threaded for the reception of an externally threaded shaft 22 to which a weight 23 is rigidly attached. As shown, the weight 23 is threaded onto a reduced portion 24 of the shaft 22 and the end of the shaft is peened 35

over as at 25 to permanently attach the weight 23 to the shaft.

The threads on the shaft 22 are of a high lead whereby when the shaft 22 is rotated it will 5 adjust the weight toward or away from the plane of the blade 12 and will give a sufficient range of adjustment within one complete revolution of the shaft. The offset 15 is of such a depth that when the weight 23 is adjusted so as to be as close as 10 possible to the bottom of the offset 15 the entire blade and its weight 23 will be statically balanced in both its horizontal and vertical positions. Then when the shaft 22 is rotated through one 15 revolution from its low to its high position the weight will be spaced from the blade a sufficient distance to give the requisite high draft that is desired at certain times.

The axis of the shaft 22 theoretically could lie anywhere on a vertical diameter of the blade and 20 the device could still be statically balanced by the use of a proper weight. However, in order that the device will operate at maximum efficiency, it has been found that the location of the axis of the shaft 22 is approximately $\frac{1}{2}$ of an inch from 25 the pivot axis 17. If the axis of the shaft 22 is moved further away from the pivot shaft 17 the action of the damper is changed so that the burner draft does not remain constant at the higher stack drafts but instead tends to decrease, 30 so that the curves of Figure 3 break over and fall off. On the other hand if the weight is moved too near to the axis 17 the action of the damper is changed so that the curves shown in Figure 3 climb gradually and do not level off.

35 The weight necessary to balance the various sizes of regulators will vary and can best be determined by experiment. However, as a practical matter, the thickness of all of the weights should be the same in order that the depth of 40 the depression or offset 15 can be kept the same for each side of the blade. The mass of the weight 23 can be varied by changing its diameter. It has been found that a depth of offset of $\frac{1}{2}$ of an inch is suitable, although this dimension is 45 not critical. The thickness of the weight is dependent on the depth of the offset.

The weight 23 is of substantially frusto-conical shape so that the center of gravity thereof is not 50 at the center of the weight but is offset slightly toward the plane of the blade. The weight 23 is provided with a substantially circular recess 26 into which is inserted a packing of felt 27 or the like which is preferably fixed to the interior surface of the recess 26 by a cement that will not 55 char or harden. The felt 27 fits snugly against the exterior surface of the sleeve 21 to prevent corrosion of the surface of said sleeve and the deposit of soot thereon.

The end of the shaft 22 opposite the weight has 60 a pointer 28 and a knob 29 attached thereto in the same manner as the weight 23. The knob provides for rotation of the shaft 22 and the pointer indicates the relative position of the weight.

65 A stop 30 is attached to the ring 11 adjacent one end of the pivot shaft 17. A lower portion 31 of the stop is substantially in the plane of the blade when it hangs in its vertical position and is located on the exterior surface of the ring 11 so that the major segment 19 of the blade 12 cannot 70 swing outwardly. The upper end 32 of the stop 30 extends out from the plane of the ring and is so adjusted that the major segment 19 of the blade cannot swing too far inward.

75 An auxiliary weight 33 is attached by a screw

34 adjacent the lower edge of the major segment 19 of the blade 12. This weight is readily removable, as in some cases its use is unnecessary.

The auxiliary weight 33 is necessary only when the pipe 10 is attached to a vertical flue outlet 5 or stack extending from the combustion chamber. Ordinarily the draft regulator is mounted so close to the usual flue outlet or stack that when the blade 12 rotates any substantial amount from its vertical position the lower portion 19 of the 10 blade 12 will extend into the path of the rapidly moving hot gases emanating from the combustion chamber. If the draft regulator is mounted on a vertical stack as aforementioned, when the blade 12 swings into the path of the gases they 15 will impinge on the lower portion of the blade and will tend to upset the required balance of the regulator as a whole. Consequently, the weight 33 is used to offset the force of the rapidly moving gases when the regulator is mounted in a 20 vertical stack.

If the regulator is mounted on a horizontal flue outlet, however, the plane of the blade 12 will lie in the path of the gases escaping from the combustion chamber when it is swung to its inward position, and consequently, the gases will have no effect on the position of the blade. In such a case the weight 33 is dispensed with.

When the burner is in operation, the hot gases escaping up the stack create a draft in the burner 30 that supplies air for combustion. The draft thus created fluctuates widely due to changes in atmospheric pressure and temperature, and also to variations in wind velocity and direction. The automatic draft regulator above described swings 35 on its pivot as the draft within the stack changes and allows more or less air to enter through the pipe 10, thereby keeping the burner draft substantially constant.

By rotating the threaded shaft 22 the weight 40 23 may be moved toward or away from the blade, thus changing the air pressure required to swing the blade 12 about its pivot. Once the weight has been adjusted to give a certain burner draft, measured in inches of water, the regulator will 45 hold that draft substantially constant, despite variations in the stack draft, and the burner will operate at its maximum efficiency.

The curve sheet shown in Figure 3 of the drawing indicates the marked difference produced by 50 this invention over draft regulators of previous designs. This difference is primarily due to the formation of the offset 15 so that the weight 23 can be adjusted to a point where the center of gravity of the weight and shaft lie substantially 55 in the plane of the blade 12. The three curves shown in full lines in Figure 3 show results of tests on the regulator of this invention, whereas the three curves shown in dotted lines represent the operation of a regulator identical with 60 the one herein shown except that there is no offset 15. The curve A shows the practically constant burner draft at the low setting of the indicator 28, whereas curve A' shows the corresponding setting on the older type of regulator. 65 B and B' show the corresponding drafts at the medium setting of both devices, and C and C' show the drafts created at the high setting of both types of regulators.

The abscissae of the curves of Figure 3 are the 70 stack drafts and the ordinates are the drafts in the burner, both measured in inches of water. The stack drafts range from 0 to .2 inch or possibly even higher under certain conditions. The burner draft at low setting (curve A) is about .02 75

- inch and, as will be seen, does not vary over approximately .01 of an inch after the blade begins to open. It requires a stack draft of .04 inch or more to produce a burner draft of .02 inch. The 5 medium setting of the weight (curve B) gives a burner draft of between .04 and .05 inch with stack drafts of .07 inch and up, and the high setting (curve C) gives a burner draft of about .08 inch with stack drafts of .11 and up.
- 10 If the blade 12 could be fitted tightly into the ring 11, there would be no leakage of air past the blade when the latter is in its closed position. Therefore, the curves would all lie on a straight line at an angle of 45 degrees to both the X and Y, 15 or stack draft and burner draft axes from zero draft to the points where the blade begins to open. In other words, the stack drafts and burner drafts would be equal up to the points where the blade begins to swing on its pivot. At 20 these points the various curves would break away from the straight line.

Because there is always a certain amount of leakage, however, the curves are not on one straight line at low drafts, and the inclination 25 of the curves is not 45 degrees. The leakage accounts for the difference between the curves at low drafts.

The curves A', B' and C' rise higher than curves A, B and C and do not level off because 30 the weight is spaced farther from the blade at each setting than it is at the corresponding setting on the blade of this invention. Consequently a higher stack draft is required to move the blade of the previous type than is necessary 35 in the device disclosed herein.

Comparing the results obtained with the two regulators it will be apparent that with the former type the burner draft rises continually as the stack draft increases, and does not level off 40 and become constant when the proper operating stack draft is reached. With the regulator described herein, however, the burner draft remains practically constant despite fluctuations in the stack draft.

45 Not only does the invention disclosed herein hold the draft in the burner substantially constant within the usual operating range of stack drafts, but it also makes possible the proper control of the lower burner drafts, such as drafts of .02 inch of water.

It will be readily apparent that the invention herein disclosed is a marked improvement over prior adjustable draft regulators, and I desire the invention to be limited only by the scope of the 55 appended claims.

I claim:

1. A draft regulator for combustion apparatus comprising a frame member having an opening therein, a circular blade of a size to substantially completely fill said opening, said blade being pivoted on said frame member on an axis in the plane of the blade and coincident with a chord of said circular blade subtending 152 degrees of arc, thereby dividing said blade into a major segment and a minor segment, an offset in the minor segment of the blade and a weight mounted in 10 the offset for adjustment normal to said blade, said weight being of such size that the blade is statically balanced in both its vertical and horizontal positions when the weight is in the position closest to the blade. 15

2. A draft regulator for combustion apparatus comprising, in combination, a frame member having an opening therein, a blade of a size to substantially completely fill said opening, said blade being mounted in said frame member on a pivot located above the center thereof thereby dividing said blade into a major segment and a minor segment, an offset in the minor portion of said blade forming a recess therein, a weight adjustably mounted for movement perpendicular to said 25 blade and into and out of said recess and movable to a position wherein the center of gravity of said weight is substantially in the plane of the blade, said weight being of such size that its weight plus the weight of the minor portion of 30 the blade equals the weight of the major portion of the blade, and said weight being so located with respect to the pivot axis of the blade that when the weight is as close as possible to said blade the turning movement of the two sides of 35 the blade are substantially balanced.

3. A draft regulator for combustion apparatus comprising a frame member having an opening therein, a circular blade of a size to substantially fill said opening, said blade being pivoted on said 40 frame member on an axis in the plane of the blade and coincident with a chord of said blade located at one side of the center thereof thereby dividing said blade into a major segment and a minor segment, an offset forming a recess in the minor segment of the blade, and a weight mounted in the offset for adjustment normal to said 45 blade, said weight being of such size that its weight plus the weight of the minor portion of the blade equals the weight of the major portion 50 of the blade and said weight being so located with respect to the pivot axis of the blade that when the weight is as close as possible to said blade the turning moments of the two sides of the blade are substantially balanced. 55

JOHN W. MILLER.

CERTIFICATE OF CORRECTION.

Patent No. 2,194,608.

March 26, 1940.

JOHN W. MILLER.

It is hereby certified that error appears in the printed specification of the above numbered patent requiring correction as follows: Page 3, second column, line 35, claim 2, for the word "movement" read --moment--; and that the said Letters Patent should be read with this correction therein that the same may conform to the record of the case in the Patent Office.

Signed and sealed this 7th day of May, A. D. 1940.

(Seal)

Henry Van Arsdale,
Acting Commissioner of Patents.
